UNITED STATES PATENT OFFICE.

JOSEPH WEINHARDT, JR., OF ST. LOUIS, MISSOURI.

DESIGN FOR A DOUCHE-PAN.

46,486.

Specification for Design.

Patented Sept. 29, 1914.

Application filed August 4, 1914. Serial No. 855,069. Term of patent 14 years.

To all whom it may concern:

Be it known that I, JOSEPH WEINHARDT, Jr., a subject of the Emperor of Austria-Hungary, residing at St. Louis, in the State of Missouri, have invented a new, original, and ornamental Design for Douche-Pans, of which the following is a specification, reference being had to the accompanying drawing, forming part thereof.

The figure is a perspective view, showing my new design.

I claim:

The ornamental design for douche pan, as shown.

JOSEPH WEINHARDT, Jr.

Witnesses:

JAMES C. RAUSCH,
KASPAR GOETZ.
